UNITED STATES PATENT OFFICE.

GEORGE W. RISTINE, JR., OF CHICAGO, ILLINOIS, ASSIGNOR TO PRESSED STEEL CAR COMPANY, OF PITTSBURGH, PENNSYLVANIA, A CORPORATION OF NEW JERSEY.

DISCHARGE-DOOR-OPERATING MECHANISM.

1,225,176.

Specification of Letters Patent.

Patented May 8, 1917.

Application filed December 24, 1915. Serial No. 68,528.

To all whom it may concern:

Be it known that I, GEORGE W. RISTINE, Jr., a citizen of the United States, residing at No. 1716 East Fifty-fifth street, Chicago, 5 in the county of Cook and State of Illinois, have invented certain new and useful Improvements in Discharge-Door-Operating Mechanism, of which the following is a specification.

10 This invention relates to railway dump cars, including that type known as a general service car, some types of which are illustrated and described in United States Letters Patent No. 791,348, granted to C. A. 15 Lindström and John F. Streib, in which the bottom is partly or substantially composed of a plurality of discharge doors which are hinged along one edge, and which at their free edges are supported by the operating 20 shafts which have heretofore been supported in stationary bearing members secured to the transverse members of the underframe, and an object of the invention is to provide means for supporting the operating shafts 25 independently of the transverse members of the underframe, which means will take the place of or be auxiliary to the ordinary bearing members secured to the transverse members of the underframe. 30 Another object of the invention is to provide movable means for supporting a bodily movable discharge door operating shaft from the side wall of a car.

A further object of the invention is to 35 provide a discharge door operating mechanism, for railway dump cars, having a movable member adapted to be moved by the door operating shaft into or out of supporting position relative to said shaft.

40 With the above and other objects in view, the invention resides in the construction, arrangements and combinations of parts hereinafter described and claimed.

Referring now to the drawings in which 45 like reference characters refer to like parts, Figure 1 is a plan view of a car embodying the invention, Fig. 2 is a side elevational view of the same, a portion of one of the side stakes being broken away to more clearly 50 show a portion of the door operating mechanism; Fig. 3 is an enlarged cross sectional view taken on the line 3—3 of Fig. 1; Fig. 4 is an enlarged detail side elevational view of a portion of the car, the side stake being 55 omitted to more clearly illustrate the inven-

tion; Fig. 5 is a sectional view taken on the line 5—5 of Fig. 4, the side stake being shown, and Fig. 6 is a sectional view taken on the line 6—6 of Fig. 4, portions of the side walls being removed to more clearly 60 illustrate the invention. The description being confined to that portion of the car which is illustrated, it will be understood that the opposite end of the car is in all respects similar to that which is shown. 65

Referring now in detail to the drawings, 1 indicates the center sill, 2 the end sill, 3 the bolster, and 4 and 5 the intermediate transverse members of the underframe, all of which may be of any desired construction 70 and suitably connected.

6 indicates the car body which comprises end walls 7 and side walls 8, all of which are suitably connected. The side walls 8 are each preferably provided with a vertical upper portion 9, a downwardly and inwardly sloping intermediate portion 10, and a horizontal lower portion 11, such horizontal portion preferably resting on and being secured to the end portions of the transverse members of the underframe. To stiffen the body of the car the side walls, at intervals throughout their length, are provided with stakes 12. 75 80

The lower edge portions of the side walls, 85 as indicated at 13, and the upper edge portions of the center sill and transverse members of the underframe define discharge openings in the car bottom, which openings are closed by doors 14 and 15, which are 90 preferably hinged along their edge portions to bracket members suitably connected with the center sill 1.

To operate the discharge doors 14 and 15 and for the purpose of supporting such doors in their closed positions, shafts 16 are provided. In the embodiment of the invention as shown in the drawings, each of these shafts is rotatably and slidably mounted in slots formed in the members 17 which are 100 preferably secured to the bolster and transverse members, and are also mounted in a movable member 18 which is hereinafter more fully described. To each of these shafts is preferably secured a plurality of 105 spirally grooved drums 19, to each of which a chain 20 is connected, the other end of the chain being connected to the free edge of one of the doors, preferably through the medium of a member 21 which is connected 110

with the door. This member 21 is provided with a serrated shoe portion 22 which is adapted to engage with a serrated roller 23 secured on the operating shaft, which roller 5 may be integral with the spirally grooved drum 19.

Intermediate the transverse members 4 and 5 of the underframe a bracket member 24 is provided having a top portion which is 10 preferably secured to the horizontal portion 11 of the side wall and having a side portion secured to one of the side stakes 12. This member is preferably provided with spaced vertical ribs 25 which are preferably 15 integral with the top and side portions and are provided with notches 26 open at one end adapted to receive the shaft 16. These ribs 25 support the shaft 16 directly when such shaft is in the notches 26. Between the 20 ribs 25, rollers 27 and 28 are mounted on pins 29 and 30, which pins are held against longitudinal movement by cotters or other suitable means. The member 18 is movably mounted on the roller 28, and at its end portion 25 31 is preferably provided with a notch 32 in which the shaft 16 is rotatably mounted. It will be understood that if desired the notch 32 may be modified and the end portion of the member 18 formed in any other 30 suitable manner to provide a bearing for the operating shaft. When the operating shaft is in the position as shown in the left hand portion of Fig. 3, and Figs. 4, 5 and 6, the upper surface of the end portion 33 of the 35 member 18 will contact with the roller 27 and will thus support and prevent any downward movement of the shaft 16.

Assuming the doors to be in closed position and it is desired to open them, the operator by the use of lever 34 rotates the operating shaft 16 in the direction as indicated by the arrows in the left hand portion 40 of Fig. 3 and Fig. 5, which causes the serrated roller 23 to engage with the serrated shoe member 22 on the doors 14 and 15, thus causing the shaft to move in a horizontal direction from its door supporting position, as shown in the right hand portion of Fig. 3 and in dotted lines in Fig. 5. It will be 45 noted that the movable member travels horizontally with the shaft until the shaft drops within the notches 26 formed in the vertical web portions 25 of the member 24, at which time the movable member is subjected to a 50 tilting movement, allowing such member to assume a position as shown in dot and dash lines in Fig. 5 of the drawings, and indicated by the reference character A. To prevent further movement of the movable member 55 18 around the roller 28, a stop 35 is provided, such stop being preferably integral with the vertical web members 25.

When it is desired to close the discharge doors the operator rotates the shaft 16 in 60 the direction as indicated by the arrow in

the right hand half of Fig. 3 of the drawings until the chains 20 winding on the drums 19 have raised the doors to a position above the shaft at which time the continued rotation of the shaft and the winding 70 of the chains thereon cause the shaft to move bodily a sufficient distance for the rollers 23 to engage with the shoes 22 of the member 21 to effect the final closing movement of the doors. As the shaft moves toward 75 and under the doors the member 18 will be drawn by the shaft from its non-supporting position as shown in dot and dash lines and indicated by the reference character A in Fig. 5 to its supporting position as shown in full lines in this figure. 80

To stiffen the side wall 8 above the bracket 24, triangular members 36 are preferably provided which are secured to the stake 12 and to the sloping and horizontal 85 portions 10 and 11 respectively of the side wall.

It will be understood that if desired the members 18 which have been described as being secured to the transverse members of the underframe may be dispensed with and the movable member and bracket may be substituted at intervals throughout the length of the operating shaft for the support of such 90 shaft. 95

In the drawings, the door 15 has been shown about twice the length of the doors 14, but it will be understood that if desired the door 15 may be of a length great enough to extend between the bolsters, or if desired all the doors may be made of equal length, or in other words, all the doors may be of substantially the same length as the doors 14. 100

I do not wish to be limited to the exact construction and arrangement of the parts 105 of the door operating mechanism as described in the specifications, for it will be apparent to those skilled in the art to which this invention appertains that many changes may be made without departing from the 110 spirit and scope of the invention, as set forth in the appended claims.

Having thus described the invention, what I claim as new and desire to secure by Letters Patent is: 115

1. In a dump car, a discharge door, a bodily movable shaft adapted to support said door in its closed position, and a member adapted to be moved bodily into shaft supporting position by said shaft, said member being automatically movable by said shaft out of shaft supporting position when the doors are being opened. 120

2. In a dump car, the combination with a center sill, of a discharge door hinged to said center sill, a side wall, a bracket depending from said side wall, rollers mounted in said bracket, a member movable between said rollers and a bodily movable shaft mounted in said member and adapted to be 125 130

moved into and out of door supporting position, said member being movable into and out of shaft supporting position.

3. In a dump car, the combination with 5 an underframe, of a discharge door hinged thereto, a side wall, a bracket connected with said side wall, a bodily movable shaft adapted to be moved into or out of direct supporting position with said door, and a member 10 shiftably mounted in said bracket adapted to be moved into or out of shaft supporting position.

4. In a dump car, a discharge door, an 15 operating shaft adapted to be moved into or out of supporting position with said door, and a bracket secured to said car, said bracket having a web adapted to directly support said shaft only when out of supporting position with said door.

20 5. In a dump car, a discharge door, an operating shaft adapted to be moved into or out of door supporting position, a bracket secured to said car adapted to directly support said shaft out of door supporting position 25 only, and a member mounted in said bracket adapted to move with and support said shaft in door supporting position.

6. In a dump car, the combination with a 30 center sill of a discharge door hinged to said center sill, a side wall, transverse members extending between and connected with said sill and wall, a door operating shaft mounted in said transverse members adapted to be moved in a direction transversely of the 35 car, a bracket depending from said side wall between said transverse members, and a member movably mounted in said bracket adapted to move with and support said shaft.

40 7. In a dump car, the combination with a center sill, of a discharge door hinged thereto, a side wall, a bracket connected with said side wall, a member movably mounted in said bracket, and a bodily movable shaft mounted in said member, said shaft being adapted to move into or out of supporting position with said door, and said member being movable into and out of supporting position with said shaft.

50 8. In a car door operating mechanism, the combination with a discharge door, of an operating shaft arranged to support the door when the door is raised, a flexible connection between the shaft and door, and a member adapted to move with said shaft into shaft supporting position, said member being movable by said shaft out of shaft supporting position when the door is dropped.

60 9. In a dump car, the combination with a center sill of a discharge door hinged to said center sill, a side wall, transverse members extending between and connected with said sill and wall, a door operating shaft mounted in said transverse members

adapted to be moved in a direction transversely of the car, a bracket depending from said side wall, and a member mounted in said bracket adapted to move into and out of supporting position with said shaft, said member being movable by said shaft in a direction at an angle to the longitudinal axis of said shaft.

70 10. In a dump car, a discharge door, a bracket member comprising spaced vertical 75 ribs, a member adapted to extend across the space between said ribs, a bodily movable member mounted between said ribs adapted to coöperate with the last mentioned member, and a bodily movable door operating shaft mounted in and supported by said movable member.

80 11. In a dump car, a discharge door, a bracket secured to said car out of the path of said door, a member slidably mounted below said door in said bracket movable into and out of the path of said door, and a bodily movable door operating shaft mounted in and supported by said member and adapted to be carried by said member into 90 and out of the path of said door.

85 12. In a dump car, a discharge door, a bracket mounted on said car, a door operating and supporting shaft movable into and out of engagement with said door, and a movable shaft supporting member mounted in said bracket, said member being adapted to relieve itself of the weight of said shaft and transfer it directly to said bracket when said door is opened.

100 13. In a dump car, a discharge door, a shaft for operating and supporting said door, a bracket rigidly mounted on said car adapted to support said shaft, and means between said bracket and shaft for carrying said shaft into engagement with said bracket when the door is opened and out of engagement with said bracket when the door is closed.

110 14. In a dump car, a discharge door, a bodily movable shaft for operating and supporting said door, a bracket mounted on said car adapted to support said shaft, said bracket having a notch formed therein adapted to receive said shaft when the door 115 is opened and means mounted in said bracket for carrying said shaft into and out of said notch and into and out of engagement with said bracket.

120 15. In a dump car, a discharge door, a bodily movable shaft adapted to support said door in its closed position, and means for supporting said shaft, said means being shiftable by said shaft out of shaft supporting position when the door is opened.

125 16. In a dump car, a discharge door, a bodily movable shaft adapted to support said door in its closed position, and means for supporting said shaft when the doors are closed, said means being slidable to a 130

non-supporting position relative to said shaft when the doors are open.

17. In a dump car, a discharge door, a bodily movable shaft adapted to support said door in its closed position, a bracket, a member mounted in said bracket for supporting said shaft, said member being movable bodily by said shaft out of shaft supporting position when the door is opened, and means on said bracket adapted to limit the movement of said member when said member is out of shaft supporting position.

18. In a dump car, a discharge door, a bodily movable shaft for operating said door, a bracket mounted on said car, said bracket comprising a plurality of spaced vertical ribs, members extending transversely across the space between said ribs, and means for carrying said shaft into and out of engagement with said door, said member being mounted between said transverse members and adapted to be moved back and forth between said ribs.

19. In a dump car, a discharge door, a bodily movable shaft for operating said

door, a bracket secured to said car, and means mounted in said bracket for carrying said shaft into said bracket when the door is being opened.

20. In a dump car, a discharge door, a bodily movable shaft for operating said door, a bracket secured to said car, and means mounted in said bracket for carrying said shaft into said bracket when the door is being opened, said member being movable bodily in the direction of its length.

21. In a dump car, a discharge door, a bodily movable shaft for operating said door, a bracket secured to said car, and means mounted in said bracket adapted to carry said shaft into said bracket when the door is opened, said means being adapted to move bodily relative to said bracket, a distance equal to the travel of said shaft.

In testimony whereof I affix my signature in presence of two witnesses.

GEORGE W. RISTINE, JR.
